HOME AQUARIUM FILTER

David D. Lovitz, Short Hills, N.J., assignor to Sternco Industries, Inc., Harrison, N.J.

Filed Nov. 19, 1971, Ser. No. 200,647

Term of patent 14 years

Int. Cl. D30—02

U.S. Cl. D30—9

FIG. 1

FIG. 2

FIG. 3

FIG. 4

FIG. 1 is a front view of a home aquarium filter showing my new design.

FIG. 2 is an end view thereof.

FIG. 3 is an opposite end view thereof.

FIG. 4 is a top view thereof.

The rear view is the same as the front view, and the bottom view is plain.

I claim:

The ornamental design for a home aquarium filter, as shown and described.
